UNITED STATES PATENT OFFICE.

HENRY MARTIN GAIN, OF BELLEVILLE, ONTARIO, CANADA.

TRAIN-STOP.

1,149,571.

Specification of Letters Patent. Patented Aug. 10, 1915.

Application filed February 27, 1914. Serial No. 821,394.

To all whom it may concern:

Be it known that I, HENRY MARTIN GAIN, a subject of the King of Great Britain, and resident of 302 Bleeker avenue, in the city 5 of Belleville, in the county of Hastings, Province of Ontario, in the Dominion of Canada, have invented certain new and useful Improvements in Train-Stops, of which the following is a specification.

10 The invention relates to improvements in train stops as described in the present specification and illustrated in the accompanying drawings that form part of the same.

The invention consists essentially in the 15 novel construction and arrangement of parts whereby the train is brought to a standstill by certain mechanism with electric and pneumatic attachments.

The objects of the invention are to eliminate 20 accidents due to collisions and derailments of railroad trains, to take over the control of the train under such circumstances from the regular attendant and generally to provide a cheap, simple and efficient means of safeguarding lives and property.

In the drawings, Figure 1 is a perspective and diagrammatic view of the operating mechanism. Fig. 2 is a plan view of the 30 bracket and operating mechanism. Fig. 3 is a side elevation of an electrical track contact. Fig. 4 is a plan view of a portable contact frame. Fig. 5 is an end elevation of the track contacts and railway rails.

35 Like numerals of reference indicate corresponding parts in each figure.

Referring to the drawings, 1 is a bracket in the locomotive cab, conveniently situated to the throttle.

40 2 is a rotatable circular valve mounted on the bracket 1 and having the diametrical port 3 therethrough and the recess 4 at one side thereof.

45 5 is a pinion fixedly mounted centrally on the top of the valve 2 being supported on the shaft 6 projecting upwardly from the journal 7.

50 8 is a circular casing having the flange 9 rigidly secured to the bracket 1 and the journal bearing 10 receiving the journal 7, and also having the inlet port 11 diametrically opposite the outlet port 12, said ports registering with the port 3, and the exhaust

port 13 adapted to register with the recess 4 for the release of trapped air. 55

14 is a compressed air tank connected with the port 11 by the pipe 15.

16 is an electro-magnet secured to the underside of the top of the frame 17 the latter being supported on the bracket 1 adjacent 60 to the valve 2, said electro-magnet 16 being included in a circuit 18 energized by the electric batteries 19 or from any other suitable source of current.

20 and 21 are casings preferably secured 65 at the front of the locomotive between the rails on which the said locomotive travels.

22 and 23 are shoes inclosed in the casings 20 and 21 respectively and resiliently held to their lower positions by the springs 70 24 and 25, said shoes projecting below said casings and carrying at the lower ends the electric brushes 26 and 27, said brushes being included in said circuit 18 and normally forming the break in said circuit. 75

28 and 29 are T-shaped electrical contacts electrically joined by the rod 30 the latter forming the electric switch arm which together with said contacts and said brushes closes the break in said circuit 18 and energizes the electro-magnet 16. The said contacts 28 and 29 are pivotally secured in the frame 30 between the rails on which the locomotive travels. The lower ends of said contacts are pivotally connected to a rod 80 31, the latter being pivotally joined to one section of the crank lever 32, which is also connected to the semaphore arm 33, of course this part of the mechanism may be changed to suit the different mechanisms pertaining 85 to various signal systems, but in the means described the raising of the semaphore arm swings the contacts 28 and 29 on their pivots and sets them upright where they are brushed by the brushes 26 and 27 in order to 90 prevent the locomotive rushing past the semaphore signal.

95 34 is a cylinder closed at each end and supported on the feet 35 and on the bracket 1, and extending partly over the casing 8 in 100 the direction of the pinion 5, said cylinder having the inlet 36 centrally through the closed end thereof.

105 37 is a cylinder in alinement with the cylinder 34, having its open end opposite the inner end of the cylinder 34 and its closed

end 38 adjacent to the magnet frame 17, said cylinder 37 being supported on the feet 39 on the bracket 1 and extending part way over the casing 8 in the direction of the 5 pinion 5.

40 is a piston operating in the cylinder 34. 41 is a piston operating in the cylinder 37. 42 is a toothed rack coacting with the pinion 5 and joining the pistons 40 and 41, so that 10 any movement of said pistons will immediately actuate pinion 5 and consequently turn the rotatable valve 2.

43 is a spring of any suitable type, though here shown as a helical spring between 15 the piston 41 and the closed end 38 of the cylinder 37, the tendency of said spring 43 being to move the piston 41 to the open end of the cylinder 37, and the piston 40 to the closed end of the cylinder 34, and 20 to move the valve 2, so as to bring the port 3 into register with the ports 11 and 12.

44 is a rod from the piston 41 extending outwardly through the correspondingly squared orifice in the closed end 38 and having 25 the notched end 45.

46 is the armature of the electro-magnet 16, said armature being pivotally secured in the bracket 47 extending downwardly from the top of the frame 17 and having the 30 notched end 48 corresponding with the notched end 45 and engaging said rod 44 in its lower position, though released from said rod 44 by the energization of the magnet 16 as said magnet picks up the armature 35 and lifts it out of engagement with the notch 45. The armature 46 engages the rod 44 in the compressed position of the spring 43 and the armature and the rod by means of their notched ends hold the said spring compressed 40 until released by the closing of the circuit 18, otherwise by the contacting of the brushes 26 and 27 with the contacts 28 and 29.

49 is a cylinder having the inlet 50 45 through one of its heads and the outlet 51 through the side wall thereof, intermediate of its length.

52 is a piston operating in the cylinder 49. 53 is a piston rod extending outwardly 50 through the head of the cylinder 49 from the piston 52, and engaging the throttle lever 54.

55 is a pipe leading from the outlet port 12 of the valve casing 8 to the inlet port 50 55 of the cylinder 49, thereby establishing communication between the compressed air reservoir 14 and the cylinder 49, on the operation of the pistons 40 and 41, the latter being actuated by the spring 43, consequently 60 operating the piston 52 and moving the throttle lever 54 to its closed position.

56 is a cylinder closed at one end 57 and having the inlet 50 through said closed end.

59 is a piston operating in the cylinder 50. 65 60 is a piston rod extending from the

piston 59 and pivotally joined to the brake lever 61, said brake lever operating with a spring pawl over the toothed disk 62, consequently remaining in the position to which it is moved until manually changed. 7

63 is a pipe tapping the pipe 55 adjacent to the cylinder 49 and leading to the inlet 58 and so establishing communication from the compressed air reservoir 14 to the cylinder 56 and automatically operating the brake 7 mechanism.

64 is a pipe connecting the exhaust opening 51 with the cylinder 34.

In the operation of this invention it will be seen that the track contact frame is made up, so that it can be rigidly secured at any point that may be desired, preferably directly opposite a semaphore signal or switch, thus there will be an operating lever from the mechanism operating the semaphore arm or from the switch mechanism. This will insure setting upright the track contacts, which are pivotally secured in the frame held between the rails of the trackway. In their upright position these contacts must be brushed by the brushes at the end of the shoes from the locomotive and these close the local circuit in the cab of the locomotive, which energizes the electro-magnet 15, with the result that the armature 46 is lifted and thus becomes disengaged from the rod 44. The spring 43 now comes into action, and drives the piston 41 to the open end of the cylinder 37 and the piston 40 to the closed end of the cylinder 34, as explained in the foregoing, and turns the valve 2. The air from the reservoir 14 flows through the valve into the cylinder 49 and into the cylinder 56, operating throttle and brake levers as described. The air exhausting from the cylinder 49 through the outlet 51 flows through the pipe 64 into the cylinder 34 and through the inlet 36 and drives the piston 40 back to its original position and consequently the piston 41 against the pressure of the spring 43. The electrical circuit being broken by the passage of the locomotive off the contacts 28 and 29 leaves the armature 46 in its lower position, therefore the notched rod 44 will engage said armature 46 and thus hold the piston 41 adjacent to the closed end 38 of the cylinder 37 and the spring 43 compressed between said piston and said closed end until the next operation of the device occurs.

This train stop mechanism is particularly adaptable to act in conjunction with the present efficient signal systems and while a very simple connection has been shown, it must be understood that the present invention is intended to be used with the most modern signal devices.

It is well known that most of the accidents that occur are through the negligence of the railroad engineers to rush signals in

- their anxiety to keep to the schedule time, and it is to avoid this and put it beyond the power of the engineer to avoid stopping that this invention has been devised, and it
- 5 is not intended that the invention shall be used independently of existing apparatus, but of course it may be successfully operated with any new or old railroad device that will serve the purpose of putting the contacts
- 10 into or out of position, and further, this invention may be used with other motive power than compressed air, though the latter in nearly every case will be most convenient.
- 15 The various parts need not necessarily be constructed and arranged as described herein, but may be varied according to the scope of the claims for novelty following this description.
- 20 What I claim is:—
1. In a train stop, a source of electrical energy and contacts apart from the vehicle, a fluid supply, a fluid valve, a throttle lever, a rack and pinion mechanism for opening 25 and shutting said valve automatically, an armature normally connected with said rack and maintaining said valve in its shut position, electrical means for releasing said armature from its engagement, mechanical means for operating said throttle actuated by said fluid supply, the latter governed by said valve, and connections from said 30 throttle operating means to said valve operating means for conveying fluid to return 35 the valve operating means to its normal position.
  2. In a train stop, a source of electrical energy and contacts apart from the vehicle, a fluid supply, a fluid valve, an operating 40 lever connected with the train arresting mechanism, a fluid cylinder and piston operating therein connected with said operating lever and with said fluid supply through said valve, an electric device energized from said source and in operating relations with a pivoted armature, a spring operated rack 45 coating with a pinion for opening said valve normally held from operation by said armature and fluid means connected with said cylinder for returning said spring operated 50 rack to its normal position after operation.
  3. In a train stop, a source of electrical energy and contacts apart from the vehicle, an air reservoir, a rotary air valve, a pinion 55 mounted on the stem of said valve a rack connecting with said pinion and having plungers mounted thereon, cylinders containing said plungers, a spring exerting pressure on a plunger and driving said rack to open said 60 valve, an electro-magnet having its armature normally engaging said rack against said spring pressure, an arresting lever and pneumatic means for operating said arresting lever connected to said fluid supply 65 through said valve and having the exhaust
- therefrom connected to one of said plunger cylinders for driving said plungers and bringing said rack into engagement with said armature.
4. In a train stop, a vehicle, a pair of 70 brushes attached to said vehicle, a pair of track contacts, a local circuit suitably energized and connected to said brushes, an electromagnet in said circuit and a pivoted armature lifted by said magnet, said armature 75 having a latch end, a pair of cylinders, pistons operating in said cylinders, a rod joining said pistons, a spring driving one of said pistons and consequently the other, a rod connected to said directly driven piston 80 having a latch end engaging said armature in the lower position of said armature, a valve operated by said rod joining the pistons, an expansile fluid tank, a cylinder connected through said valve to said expansile fluid tank and a piston operating in the latter cylinder, a vehicle control lever operatively connected with the latter piston and connections from said control lever cylinder to one of said valve operating cylinders for 90 the flow of expansile fluid to drive said valve gear pistons against said spring pressure and connecting the armature and the rod from the spring driven piston.
5. In a train stop, a circular rotatable 95 valve having a diametrical port there-through, a central circular boss on top thereof, a pinion supported above said boss, a casing having an inlet port and an outlet port diametrically arranged in relation to one another and a circular opening in the center thereof forming a journal bearing round the edges of said opening for said valve, a pair of cylinders, pistons operating in said cylinders, a toothed rack joining said pistons 100 and coacting with said pinion and means for driving said pistons to open said valve, means for returning said pistons to their normal position, an expansile fluid tank, a cylinder and a piston operating therein, a vehicle control lever operatively connected to the latter piston, a pipe joining the latter cylinder to the outlet in said valve casing, and a pipe connecting the expansile fluid tank to the inlet in said valve casing.
6. In a train stop, a pair of track contacts, a pair of brushes carried by the vehicle, a local electrical circuit within said vehicle and connected to said brushes, means for energizing said circuit, an electro-magnet in 1 said circuit, an armature pivotally supported and having a notched end, a pair of cylinders, a pair of pistons operating in said cylinders, a rod joining said cylinders and said pistons, a rod extending from one of said pistons through a cylinder head and having a notched end engaging said notched end of the armature in the lower position of the latter, a spring behind one of said pistons for driving the said pistons, a rotatable air 1

valve operated by the movement of said pistons, a compressed air tank connected through said valve, a cylinder, a piston in the latter cylinder, a throttle lever connected 5 to said latter piston, said cylinder being connected to said compressed air tank through said valve, a pipe tapping said connection to the air tank adjacent to said throttle lever operating cylinder, a cylinder connected to

said tapping pipe, a piston operating the latter cylinder, and a brake lever operatively connected to the latter piston.

Signed at the city of Toronto, Ontario, this 23rd day of December 1913.
